UNITED STATES PATENT OFFICE.

HENRY A. CAMPBELL, OF OAKLAND, CALIFORNIA.

TWO-STROKE DEEP-WELL POWER HEAD.

Application filed February 23, 1921. Serial No. 447,311.

To all whom it may concern:

Be it known that I, HENRY A. CAMPBELL, a citizen of the United States, residing at Oakland, in the county of Alameda and State 5 of California, have invented new and useful Improvements in Two-Stroke Deep-Well Power Heads, of which the following is a specification.

This invention relates to a two-stroke deep 10 well power head.

A two-stroke pump consists of a cylinder in which is mounted two single acting plungers, positioned to reciprocate in opposition to each other. The upper plunger is 15 usually connected with a tubular rod, and the lower plunger with an inner solid rod; a reciprocal movement being imparted to the respective rods and connected plungers by opposed cranks, cams, or otherwise. In 20 pumps of this character it is, practically speaking, impossible to obtain a uniform flow or constant capacity at the point of discharge; this being largely due to the intermittent reciprocal action of the plungers, the 25 variable plunger speed, or during the crank or cam throw, but is specially due to the dead stops produced twice during each revolution when the plungers reach the ends of their respective strokes. In other words, it 30 may be stated that column of water, under ordinary circumstances, is intermittently or successively lifted by the plungers, and that the entire water column practically reaches a dead stop at the end of each plunger stroke. 35 Detrimental vibration is thus produced, a pulsating discharge obtained, unnecessary power consumed, and wear and tear generally increased.

The object of the present invention is to 40 generally improve pumps of this character, to simplify the construction of the same, and especially to provide a pump head mechanism whereby a reciprocal movement may be transmitted to the rods and connected plungers in such a manner that the movement of a column of water in a well will be absolutely uniform.

Another object of the present invention 50 is to provide a pump head structure in which cranks, cams and the like may be entirely eliminated, and furthermore to provide a mechanism which will permit a plunger stroke of ten feet or more without materially increasing the size or weight of the mechanism or the final cost to any extent.

Further objects will hereinafter appear.

The invention consists of the parts and the construction, combination and arrangement of parts as hereinafter more fully described and claimed, having reference to the 60 accompanying drawings, in which—

Figs. 1 and 2 show respectively a side elevation of the pump head drive, Fig. 1 the lower portion thereof, and Fig. 2 the upper portion.

Fig. 3 is a cross section on line 3—3, Fig. 1.

Fig. 4 is a cross section on line 4—4, Fig. 1.

Fig. 5 is a cross section on line 5—5, Fig. 1.

Fig. 6 is an enlarged detail view partly in section showing one of the crossheads. 70

Fig. 7 is a longitudinal vertical section of the pump cylinder showing the position of the plungers and the foot valve therein.

Fig. 8 is a front view of the pump head drive showing the position of the endless 75 cable.

Figs. 9 and 10 are diagrammatic views showing the relative movement of the respective cross-heads and the plungers actuated thereby.

Referring to the drawings in detail, A indicates the cylinder of a deep well pump, 2 a foot valve of suitable construction mounted in the lower end thereof, and 3 and 4 a pair of plungers adapted to reciprocate in opposition to each other. The upper plunger is connected with a tubular rod 5, while the lower plunger is connected with an inner solid rod 6; a reciprocal movement being imparted to the rods and the connected plungers by the mechanism generally indicated in Figs. 1 and 2 which forms the subject matter of the present invention.

This mechanism consists of an endless chain 7 of suitable construction, which is carried by a plurality of sprocket wheels 8, 9 and 10; said sprocket wheels being supported by journal members 11 secured to a vertically disposed frame, which consists of a pair of interspaced channel bars 12 suitably supported by a base frame 13 disposed on one side of the upper end of the well casing as indicated at 14. The endless chain 7 is driven from any suitable source of power by means of a pulley 15, a pinion 16 and a gear 17; the gear 17 being secured on a shaft 18 upon which is keyed the sprocket 8. The intermediate sprocket 9 and the upper sprocket 10 merely serve as idlers as far as the chain itself is concerned, but they co- 100

105

110

operate with the plunger reciprocating mechanism as will hereinafter be described. Suitably secured to the main frame, consisting of the channel bar sections 12, and 5 in front thereof, by bracket members 19, is a pair of upper and lower cross-head guides 20 and 21. Also supported by the brackets 19 is an upper and a lower set of track members as indicated at 22 and 23. Slidably 10 mounted between the upper cross-head guides 20 is a cross-head 24, and similarly mounted between the lower set of cross-head guides is a cross-head 25. These guides are identical in construction, and each carries 15 a pair of pivotally attached lifting rods 26, the lower ends of which terminate in lifting lugs 27. The tubular rod 5 is attached to the lower cross-head, as at 28, see Fig. 6, while the inner solid rod is connected 20 with the upper cross-head 24; the lifting rods 26 being pivotally mounted on the opposite sides of the respective cross-heads to straddle the rods as shown. The cross-heads may be constructed in any suitable 25 manner, but are in this instance provided with rollers 29, which are engaged by the respective cross-head guides.

In actual operation, referring to Fig. 2, it will be seen that the cross-head 24 has 30 reached the upper limit of its stroke, and that the lifting lugs 27 formed on the lower ends of the lifting rods 26 are being engaged by the teeth of the upper sprocket 10 and thus forced outwardly from between 35 the links of the chain. This outward movement causes the lifting rods to swing about their pivotal connections on the cross-head, and simultaneously swings the lifting lugs to assume the dotted line position indicated 40 at 26^a. Rollers or pins 30 disposed on the exterior side of each lifting lug will here engage the upper ends of the tracks 22 and as the movement of the cross-head will be in a downward direction, it is obvious 45 that engagement of the pins with the exterior surfaces of the tracks will retain the lifting lugs, and the rods to which they are attached, in a position where they are free to move in a downward direction in 50 unison with the cross-head without engaging the pins or links of the upwardly traveling chains. The downward movement will take place until the lower end of the track 22 is reached. The rods, together with the 55 lugs formed therein, will then swing inwardly; the lugs 27 passing between the links of the chain and being thereby engaged by one of the pins and immediately started in an upward direction. The inward movement of the lifting rods naturally 60 causes the rollers 30 to pass on the inside of the guide tracks, and they will therefore engage the inner face of said tracks during the upward movement; such engagement being 65 of importance as it prevents disengagement

of the lugs 27 with relation to the pins or links of the chain. In other words upward reciprocal movement is transmitted to the cross-head 24, due to engagement of the lugs 27 with one or another of the 70 links or pins of the chain; this upward movement being again transmitted to the plunger 3 through means of the solid rod 6, which is connected with the cross-head 24. The moment the upper end of the guide 75 tracks 22 is reached, automatic disengagement will take place as the teeth of the sprocket 10 will enter between the links and force the lugs 27 out of engagement therewith, the rollers 30 will engage the 80 upper ends of the tracks 22 and downward movement will take place. The operation of the lower cross-head 25, the lifting rods 26 and lugs 27 attached thereto, is identical; the only difference being that 85 the two cross-heads work in opposition to each other during the major portion of their respective strokes. It may however here be stated that while the plungers work in opposition to each other, during the major 90 portion of their respective strokes, a movement simultaneous and in unison is obtained at the end of each plunger stroke. This is accomplished by accelerating the return speed of each plunger. 95

By referring to Figs. 1 and 2, and the mechanism so far described, it will be seen that power is transmitted to lift the rods and the connected plungers by engagement of the lifting lugs with the links or pins of the chain. Means must also be provided for returning the plungers even though they might settle by gravity. This means, referring to Fig. 8, consists of an endless cable which is attached to the respective cross-heads as indicated at 40 and 41, said cable being supported and guided by pulleys 42, 43, 44, 45 and 46; the cable forming a loop when passing over the pulleys 45 and 46 and being held in a taut position by a weight 100 47. To clearly illustrate the movement of the plungers, two diagrammatic views have been submitted as shown in Figs. 9 and 10. Referring to Fig. 10, we will suppose that the straight line indicated at 50 indicates 105 the path of travel or the reciprocal movement of the lowermost plunger when traveling in an upward direction, and that the straight line which terminates in an upward hook or curve, as indicated at 51, see Fig. 9, indicates the downward movement of the upper plunger. The straight line 50 is equal to the straight line 52, but said line terminates in an upwardly rising portion 51. The lines 51 and 52 indicate the entire travel 110 of the uppermost plunger during its return or downward stroke and graphically illustrates that this plunger travels through a greater distance than the lowermost plunger 115 when the lowermost plunger is traveling in 120 125 130

an upward direction. The uppermost plunger when traveling downwardly reaches the lowermost portion of its stroke when the lowermost plunger reaches the approximate 5 end of its upward stroke, or the point indicated at 53. At this point the uppermost plunger forms the loop 51 and starts in an upward direction, reaching the point 54 when the lowermost plunger finally reaches 10 the upper end of its stroke indicated at 55. The same cycle of operation or movement takes place when the uppermost plunger travels in an upward direction as indicated by the straight line 56. During this movement 15 the lowermost plunger travels downwardly and travels the same distance as the uppermost plunger did during its downward movement, that is the lowermost plunger reaches the end of its stroke when the uppermost plunger reaches the point 57, and the lowermost plunger is then reversed and travels upwardly as indicated by the loop 58, while the uppermost plunger is completing the remainder of its stroke. In 20 other words while the plungers travel in opposition to each other, during the major portion of their respective strokes, it can be seen that they travel in unison and in the same direction when the ends of their strokes 25 are approached. This is extremely important as it permits one plunger to relieve the other plunger of its load before said plunger stops or reverses its movement. The movement of the load, or more specifically stated, 30 the water column, is therefore bound to be constant and the speed uniform, and detrimental vibrations, etc., are entirely obviated. The accelerated speed imparted to the plungers during their downward movement is 35 accomplished by the use of the endless cable shown in Figs. 1, 2 and 8. This cable, as previously stated, is attached to the respective cross-heads as shown at 40 and 41. When the cross-head is traveling upwardly, 40 a pull will be exerted on the cable which will pull the upper cross-head 24 in a downward direction, and similarly when cross-head 24 travels in an upward direction, a pull will be exerted on the cable which will 45 cause the lower cross-head 25 to travel in a downward direction. The slight upward movement of the cross-heads in unison at the end of each plunger stroke will of course 50 produce a slight slack in the upper end of the cable and would part the lower end of 55 the cable, unless this was connected with the weight 47. This weight rises during this upward movement and instantly removes the slack in the upper end of the cable when 60 the direction of the plungers is reversed.

In most two-stroke pumps employed today two cranks and pitmans are employed in connection with two sucker rods. Such a drive produces only partially the results 65 desired for the reason that the volume and

velocity of the fluid in the column increases and decreases with the velocity of travel of the plungers, that is as the cranks leave their lower centers and pass to a position at right angles to a vertical axis, it is obvious that 70 the plunger speed is rapidly increased and decreased; furthermore that dead centers or stops are reached at the end of each stroke and as such is the case it is obvious that uniform velocity and capacity of the water column cannot be maintained. 75

There are many reasons why a constant flow, velocity and volume are desired, for instance when pumping water from deep wells or in any case where the hydrostatic 80 head is considerable, it is obvious that a uniform flow is exceedingly desirable. For instance, in some parts of the country it is very common to pump water for irrigation purposes from depths of one thousand feet below the surface, and again in the oil districts it is not at all uncommon to pump oil from three or four thousand foot levels. Now, if the pump casing is six inches in diameter and the depth four thousand feet, 85 it is obvious that the weight imposed upon the plungers and the mechanism driving the same is enormous, and that, unless this weight is kept constantly moving and at uniform speed, unnecessary strains, vibration, consumption of power and wear and tear will take place. In the present instance intermittent waves and velocity of the liquid column being raised is entirely obviated as 90 the simultaneous movement of the plungers in unison at the end of each stroke permits one plunger to take the load from the other plunger before this comes to a stop and its movement reversed. The present invention therefore not only embodies a new 95 plunger movement, but it also embodies an exceedingly novel mechanism whereby said movement can be transmitted, and while this mechanism is more or less specifically illustrated, I wish it understood that various 100 changes in form and proportion may be resorted to within the scope of the appended claims; similarly that the materials and finish of the several parts employed may be such as the experience and judgment of the manufacturer may dictate or varying uses 105 may demand.

Having thus described my invention, what I claim and desire to secure by Letters Patent is—

1. A pump power head drive for two stroke pumps comprising a cylinder, a pair of plungers mounted therein, means for imparting reciprocal motion thereto and a flexible means for accelerating the speed of the plungers when traveling in a downward direction. 125

2. A pump power head drive for two stroke pumps comprising a cylinder, a pair of plungers mounted therein, means for im- 130

- parting reciprocal motion to the plungers and continuous flexible means for accelerating the speed of the plungers during a portion of their travel.
- 5 3. A pump power head drive for two stroke pumps comprising a cylinder, a pair of plungers mounted therein, means for imparting opposed reciprocal motion to the plungers, and continuous flexible means for 10 accelerating the speed of the plungers when traveling in a downward direction whereby the plungers travel in unison and in the same direction for a predetermined distance at the end of each stroke.
- 15 4. In a pump of the character described a cylinder, a pair of plungers mounted therein, an endless member traveling at a constant uniform speed, means actuated by said member for imparting movement to the 20 plungers and means for accelerating the speed of each plunger in one direction.
5. A pump power head drive comprising a frame, a pair of sprocket wheels journaled on the frame, an endless chain supported and driven by said sprocket wheels, 25 a pair of cross-heads reciprocally mounted in the frame, and intermittently engageable means for transmitting movement from the chain to the cross-heads.
- 30 6. A pump power head drive for two-stroke pumps comprising a frame, a pair of sprocket wheels supported and journaled in said frame, an endless chain supported and driven continuously in one direction 35 with uniform speed by the sprocket wheels, a pair of cross-head guides on the frame, a cross-head reciprocally mounted between each pair of guides and intermittently engageable means for transmitting movement 40 from the chain to the cross-heads.
7. A pump power head drive for two-stroke pumps comprising a frame, a pair of sprocket wheels supported and journaled in said frame, an endless chain supported 45 and driven continuously in one direction with uniform speed by the sprocket wheels, a pair of cross-head guides on the frame, a cross-head reciprocally mounted between each pair of guides, means for transmitting 50 movement from the chain to the cross-heads, and other means for accelerating the speed of the cross-heads when traveling in a downward direction.
- 55 8. A pump power head drive for two-stroke pumps, comprising a vertically disposed frame, a pair of sprocket wheels supported and journaled in the frame, an endless chain supported and driven by the sprocket wheels, said sprocket wheels maintaining a constant uniform speed, a pair of 60 cross-head members reciprocally mounted in the frame, means for forming a driving connection between each cross-head and the chain when the cross-heads are traveling in an upward direction, and means for auto-

matically disconnecting said connection when the end of an upward stroke is reached.

9. A pump power head drive for two-stroke pumps, comprising a vertically disposed frame, a pair of sprocket wheels supported and journaled in the frame, an endless chain supported and driven by the sprocket wheels, said sprocket wheels maintaining a constant uniform speed, a pair of cross-head members reciprocally mounted in the frame, means for forming a driving connection between each cross-head and the chain when the cross-heads are traveling in an upward direction, means for automatically disconnecting said connection when the end of an upward stroke is reached, and means for returning each cross-head in a downward direction and at an accelerated speed.

10. A pump power head drive for two-stroke pumps, comprising a vertically disposed frame, a plurality of sprocket wheels supported and journaled in the frame, an endless chain supported and driven by the sprocket wheels, and maintained at a uniform speed, a pair of cross-head guides in the frame adjacent the upwardly traveling side of the chain, a cross-head member mounted in each set of guides, a lifting arm pivotally attached to each cross-head member, and a lug on the lower end of each lifting arm adapted to be thrown into and out of engagement with the links of the chain.

11. A pump power head drive for two-stroke pumps, comprising a vertically disposed frame, a plurality of sprocket wheels supported and journaled in the frame, an endless chain supported and driven by the sprocket wheels, and maintained at a uniform speed, a pair of cross-head guides in the frame adjacent the upwardly traveling side of the chain, a cross-head member mounted in each set of guides, a lifting arm pivotally attached to each cross-head member, a lug on the lower end of each lifting arm adapted to enter between the links of the chain and to be engaged thereby, means for automatically engaging the lugs with the links of the chain when the lower end of a stroke is reached, and means for automatically disengaging the lugs with relation to the links of the chain when the uppermost end of a stroke is reached.

12. A pump power head drive for two-stroke pumps, comprising a vertically disposed frame, a plurality of sprocket wheels supported and journaled in the frame, an endless chain supported and driven by the sprocket wheels, and maintained at uniform speed, a pair of cross-head guides in the frame adjacent the upwardly traveling side of the chain, a cross-head member mounted in each set of guides, a lifting arm pivotally attached to each cross-head member, a lug on the lower end of each lifting arm adapted

to enter between the links of the chain and to be engaged thereby, means for automatically engaging the lugs with the links of the chain when the lower end of a stroke is reached, means for automatically disengaging the lugs with relation to the links of the chain when the uppermost end of a stroke is reached, and means for maintaining the lugs out of engagement with the chain during the downward stroke of each cross-head.

13. A pump power head drive for two-stroke pumps, comprising a vertically disposed frame, a plurality of sprocket wheels supported and journaled in the frame, an endless chain supported and driven by the sprocket wheels, and maintained at uniform speed, a pair of cross-head guides in the frame adjacent the upwardly traveling side of the chain, a cross-head member mounted in each set of guides, a lifting arm pivotally attached to each cross-head member, a lug on the lower end of each lifting arm adapted to enter between the links of the chain and to be engaged thereby, means for automatically engaging the lugs with the links of the chain when the lower end of a stroke is reached, means for automatically disengaging the lugs with relation to the links of the chain when the uppermost end of a stroke is reached, means for maintaining the lugs out of engagement with the chain during the downward stroke of each cross-head, and other means for transmitting an accelerated speed to the cross-heads during their downward stroke.

HENRY A. CAMPBELL.
